DESIGN FOR A SPOON OR ANALOGOUS ARTICLE

Harold E. Nock, Newburyport, Mass., assignor to
Towle Manufacturing Company, Newburyport,
Mass., a corporation of Massachusetts

Application December 31, 1938, Serial No. 82,109

Term of patent 14 years

To all whom it may concern:

Be it known that I, Harold E. Nock, a citizen of the United States, residing at Newburyport, in the county of Essex and Commonwealth of Massachusetts, have invented a new, original, and ornamental Design for a Spoon or Analogous Article, of which the following is a specification, reference being had to the accompanying drawing, forming a part thereof.

In the accompanying drawing, Figure 1 is a front elevational view of a spoon showing my new design; Fig. 2 is a profile view thereof; Fig. 3 is a view, in rear elevation, of the end portion of the handle shown in Fig. 1; Fig. 4 is an enlarged, fragmentary view, in front elevation, of the outer end of the handle shown in Fig. 1; and Fig. 5 is a sectional view of the handle on the line 5—5 of Fig. 1.

My design is shown in the drawing by the full lines delineating the ornamental handle, the dotted lines indicating the conventional bowl of a spoon.

The design is delineated as embodied in the handle of a spoon but the design may also be embodied in or applied to other handles of like nature.

This application is a continuation in part of my earlier filed application, Serial No. D-77,995.

I claim:

The ornamental design for a spoon or analogous article, substantially as shown and described.

HAROLD E. NOCK.
